3 Claims. (Cl. 132—79)

The present invention relates to a mascara dispensing device.

A mascara dispensing device of the type contemplated herein consists essentially of a reservoir body for mascara in liquid condition, a cap for the reservoir body forming a container therewith, and an applicator mounted on said cap to form a unit therewith and extending into the mascara in said body.

One object of the present invention is to provide a new and improved mascara dispensing device of the general type described, which has a number of parts designed for easy assembly as a unit independently of the reservoir body and for attachment as such to the reservoir body to form a closure therefor affording an effective seal for the body.

Various other objects of the invention are apparent from the following description and from the accompanying drawings, in which

FIG. 1 is a perspective of the mascara dispensing device embodying the present invention and shown in closed condition;

FIG. 2 is an exploded perspective view of the cap unit adapted to be sealably and detachably secured to the reservoir body;

FIG. 3 is an exploded perspective view of the reservoir body unit;

FIG. 4 is a longitudinal fragmentary longitudinal section through the mascara dispensing device in closed condition;

FIG. 5 is a perspective of a stopper for a refill unit; and

FIG. 6 is a perspective of a cap for the refill unit.

Referring to FIGS. 1-4 of the drawings, the mascara dispensing device consists essentially of a reservoir body unit 10 (FIG. 3) comprising a reservoir body 11 in the form of an elongated tubular vessel open at one end and adapted to contain mascara A (FIG. 4) therein in the usual form of a viscous liquid, and a cap unit 12 (FIG. 2) for said body unit comprising a cap 13. The reservoir body 11 and cap 13 may be of metal which will not be attacked by the mascara, as for example aluminum, and may have any suitable outside finish.

Closing the mouth of the reservoir body 11 is a closure 14 permanently fitted into said body, as for example, by press-fitting to form therewith the body unit 10. This closure 14 comprises an insert 15 in the body 11, made of suitable inert material, such as aluminum, and having an intermediate cylindrical bushing section 16 retained in the mouth of the reservoir body with a close press-fit, tubular extension 17 of reduced diameter on the inner end of said bushing section extending into said body, and peripherally spaced from the wall of said body, and an externally threaded tubular extension 18 also of reduced diameter on the outer end of said bushing section projecting from the open end of the body. This closure 14 also includes a washer 19 of resilient material, such as rubber, a sealing member 20 shown in the form of a cup, desirably made of an inert plastic material, which is not attacked by the mascara and which is flexible, such as polyolefins, as for example, polyethylene. This cup 20 is fitted over the washer 19 and over the inner insert extension 17, and is permanently retained in the inside of the reservoir body 11, desirably with a press-fit. To assure the permanent retention of the cup 20 on the inner

2

insert extension 17, the cup embraces said insert extension with a press-fit, and this insert extension desirably has a plurality of anchoring rings 21 integrally formed on its periphery and embedding and digging into the peripheral wall of the cup. The plastic material of the cup 20 is yieldable enough to permit said cup, although of smooth internal contour before assembly, to be pressed over the anchoring rings 21 of the inner insert extension 17 and to hold onto said extension with a firm permanent grip after assembly.

The cup 20 has an end wall 22 with an opening 23 to allow a mascara applicator rod 24 mounted on the cap 13 and forming part of the cap unit 12 to pass freely therethrough with slight clearance and the washer 19 has a central hole 25 of diameter slightly smaller than that of the applicator rod to embrace said rod with a sealing-fit and to act as a wiper to remove excess mascara from said rod as it is withdrawn from the reservoir body 11.

The body insert 15 has a center bore 26 along its full length to permit the applicator rod 24 to pass freely therethrough with clearance.

The parts 15, 19 and 20 are permanently congregated to produce the body closure 14 in the form of a self-contained unit before being affixed to the reservoir body 11, and this closure in this form is then forced into the open end of the body for fix retention therein. It should be noted that because of the self-containing nature of the closure 14, the reservoir body 11 requires no lining, collar or similar expedient therein for retaining the parts 30 of said closure together and in proper place in the body.

The cup 20, besides retaining the washer 19 in position as part of the closure unit 14, also serves as a seal to prevent the mascara liquid from leaking past the outside of this cup along the walls of the reservoir body 11 and 35 along the inside of the cup to the bushing section 16 of the body insert. The polyethylene from which the cup 20 is made is a tough flexible material, and will yield into conforming contact with the surfaces against which it is pressed to form liquid-tight sealed junctures therewith.

The cap unit 12 includes the applicator rod 24 and closes and seals the end of the reservoir body unit 10 when applied thereto. For that purpose, there is permanently retained in the open end of the cap 13, as for example by press-fit, an insert 30 in the form of a cup, made of suitable inert material, such as aluminum, and having a knurled peripheral section 31 to assure a firm grip thereof by the embracing peripheral wall of the cap. This cap insert 30 is internally threaded to permit it to be removably screwed onto the externally threaded projecting extension 18 of the body insert 15, when the cap unit 12 is applied to the reservoir body unit 10. To seal the end of the bore 26 of the body insert 15 when the cap insert 30 is screwed into place onto said body insert, there is provided a washer 32 made of suitable resilient sealing material, such as rubber, and permanently retained in a recess 33 between the end wall 34 of the cap insert and the end of the internally threaded portion of said cap insert. This washer 32 bears against the end of the body insert 15 when the cap insert 30 is screwed onto said body insert 50 and thereby effectively seals the end of the bore 26 of said body insert against the escape of mascara liquid from said bore to the threaded juncture between the body insert and the cap insert.

The applicator rod 24 is desirably made of metal, such as aluminum and is permanently affixed to the end wall 34 of the cap insert 30. For securing the applicator rod 24 to the end wall 34 of the cap insert 30, said rod has an end section 35 of reduced diameter desirably press-fitted into a hole in said end wall and shouldered against said end wall. The washer 32 has a center hole 36 to permit the applicator rod 24 to pass therethrough and this hole is smaller in diameter than the applicator rod to effect

a tight seal around said rod by which leakage through the end wall 34 of the cap insert 30 is prevented.

The applicator rod 24, when the cap unit 12 is fully applied extends inside the reservoir body 11 close to the end wall thereof and is provided with an inner end section 37 having a plurality of circumferential grooves which are shown as helical "V" threads, but which may be square or one-half "V" in shape. These grooves may also be a series of circular grooves instead of following a helix.

The bore 26 of the body insert 15 affords sufficient clearance around the applicator rod 24 to permit the latter to be deflected from a horizontal axial position when the cap unit 12 is unscrewed from the reservoir body unit 10 but while said cap unit is in close proximity thereto, so that the free end of the applicator rod can pick up mascara liquid along the side of the reservoir body 11 even when the supply of this liquid is low. The flexibility of the plastic cup 20 permits this tilting of the applicator rod 24, even if the hole 23 in the end wall 22 of the cup should not afford enough clearance to permit this action without distortion of the cup.

In operation, after the cap unit 12 is unscrewed from the reservoir body unit 10, the cap unit is pulled away from the body unit causing the applicator rod 24 to be withdrawn axially from the body unit. As this applicator rod 24 moves through the washer 19 all the mascara on the exterior surface of said rod will be wiped off except that which is contained in the grooves of the rod section 37. The applicator rod 24 may be applied to the eyelashes so that they enter the grooves of the applicator rod section 37 and pick up the mascara therein.

When it is desired to place the cap unit 12 back on to the reservoir body unit 10, the applicator rod 24 is inserted through the closure 14 of said body unit, and the cap insert 30 is screwed back onto the threaded extension 18 of the body insert 15. The clearance afforded by the bore 26 in the body insert 15 around the applicator rod 24 serves not only to permit the applicator rod to be tilted for the purpose described, and the washer 19 to be deformed into more effective sealing contact with the applicator rod, but also serves to collect any foreign matter which has been wiped off the applicator rod by said washer upon its reentry into the reservoir body. The location of the threads on the body insert 15 externally of the clearance space around the applicator rod 24 afforded by the insert bore 26 prevents the collected foreign matter in said clearance from finding its way to the threads.

The construction of the reservoir body unit 10 can be used as part of a refill unit when such is required. For refill purposes, the reservoir body unit 10 is sold in conjunction with a stopper 40 (FIG. 5) made of resilient material, such as rubber, and comprising a head 41 and a stem 42. Housing the head 41 of this stopper 40 is a refill cap 43 (FIG. 6) in the form of a cup having a knurled section 44 and provided with internal threads by which said cap can be screwed onto the external threads of the body insert extension 18. For sealing the closure 14 in conjunction with a refill, the stopper 40 is applied so that its stem 42 extends through the bore 26 of the body insert 15 and its head 41 seats against the outer edge of the extension 18 of said insert. The stem 42 is long enough so that it extends at least partway into the hole 25 of the washer 19 and has a diameter larger than the diameter of said hole, so that when the stopper is applied as described, it sealably closes said hole. When the stopper is in that position, the refill cap 43 can be screwed over the threaded insert extension 18 of the body insert 15 to compress the head 41 of the stopper and thereby to effectively close and seal the refill unit. The reservoir body unit 10 with a fresh supply of mascara liquid, closed and sealed with the stopper 40 and cap 43 as described, can be stored, transported and sold as a unit. When the mascara liquid of the dispensing device has been consumed, the reservoir body unit 10 with its closure 14 may

be discarded and replaced by a refill, after the refill cap 43 and the stopper 40 have been removed therefrom.

While the invention has been described with particular reference to a specific embodiment, it is to be understood that it is not to be limited thereto but is to be construed broadly and restricted by the scope of the appended claims.

What is claimed is:

1. A reservoir body unit for a mascara dispensing device comprising a reservoir body in the form of a tubular vessel open at one end and adapted to contain a mascara liquid, a body insert of rigid material comprising a bushing section in said reservoir body peripherally contacting the peripheral wall of said reservoir body with a close conforming press-fit, a tubular extension at the outer end of said bushing section peripherally threaded for removable attachment of a cap unit thereto, and a tubular extension at the inner end of the bushing section of reduced diameter forming an annular space between the latter tubular extension and the inner periphery of said reservoir body in the region of the latter tubular extension, a washer of resilient material seated against the extreme inner end of the latter tubular extension, and a cup of flexible material fitted over the washer and the latter tubular extension and snugly embracing peripherally both said washer and the latter tubular extension, said cup having a peripheral wall extending into said annular space and having a close conforming peripheral sealing fit with the inner peripheral wall of said reservoir body, said washer and the end wall of said cup having aligned holes to permit an applicator rod to pass therethrough with a slide fit, one of said holes being small enough to serve as a wiper to remove excess mascara from the applicator rod as it is withdrawn from the reservoir body.

2. A refill unit for a mascara dispensing device comprising a reservoir body unit having a reservoir body in the form of a tubular vessel open at one end and adapted to contain a mascara liquid, a body insert of rigid material comprising a bushing section in said body peripherally contacting the peripheral wall of said reservoir body with a close conforming press-fit, a tubular extension at the outer end of said bushing section peripherally threaded for removable attachment of a cap unit thereto, and a tubular extension at the inner end of the bushing section of reduced diameter forming an annular space between the latter tubular extension and the inner periphery of said reservoir body in the region of the latter tubular extension, a washer of resilient material seated against the extreme inner end of the latter tubular extension, and a cup of flexible material fitted over the washer and the latter tubular extension and snugly embracing peripherally both said washer and the latter tubular extension, said cup having a peripheral wall extending into said annular space and having a close conforming peripheral sealing fit with the inner peripheral wall of said reservoir body, said washer and the end wall of said cup having aligned holes to permit an applicator rod to pass therethrough with a slide fit, the hole in said washer being small enough to serve as a wiper to remove excess mascara from the applicator rod as it is withdrawn from the reservoir body, and means for closing and sealing the open end of said reservoir body unit, said closing and sealing means being removable to permit the attachment of the reservoir body unit to the cap unit as a refill comprising a stopper of resilient material having a head seated against the outer end of the tubular extension on the outer end of said body insert, a stem extending from said head through said body insert and extending into the hole in said washer with a liquid-tight fit, and a refill cap fitted over the head of said stopper and over the latter tubular extension.

3. A mascara dispensing device comprising a reservoir body unit having a reservoir body in the form of a tubular vessel open at one end and adapted to contain a mascara liquid, a body insert of rigid material comprising a bushing section in said body peripherally contacting the

peripheral wall of said reservoir body with a close conforming press-fit, a tubular extension at the outer end of said bushing section peripherally threaded for removable attachment of a cap unit thereto, and a tubular extension at the inner end of the bushing section of reduced diameter forming an annular space between the latter tubular extension and the inner periphery of said body in the region of the latter tubular extension, a washer of resilient material seated against the extreme inner end of the latter tubular extension, and a cup of flexible material fitted over the washer and the latter tubular extension and snugly embracing peripherally both said washer and the latter tubular extension, said cup having a peripheral wall extending into said annular space and having a close conforming peripheral sealing fit with the inner peripheral wall of said reservoir body, said washer and the end wall of said cup having aligned holes to permit an applicator rod to pass therethrough with a slide fit, one of said holes being small enough to serve as a wiper to remove excess mascara from the applicator rod as it is withdrawn from the reservoir body, and a cap unit including a cap, an applicator rod secured to said cap and means for removably and sealably securing said cap to said tubular extension at

5 the outer end of said bushing section and including a cap insert having a threaded engagement with the latter tubular extension, said applicator rod extending through said body insert and through the holes in said washer and said cup and into the mascara liquid in said reservoir body.
